UNITED STATES PATENT OFFICE.

CHRESTEN TORBEN MADSEN, OF OAKLAND, CALIFORNIA.

FOLDING BED.

1,291,054.

Specification of Letters Patent. Patented Jan. 14, 1919.

Application filed October 16, 1917. Serial No. 196,817.

To all whom it may concern:

Be it known that I, CHRESTEN T. MADSEN, a citizen of the United States, residing at Oakland, in the county of Alameda and 5 State of California, have invented new and useful Improvements in Folding Beds, of which the following is a specification.

This invention relates to a folding bed.

One of the objects of the present invention is to provide a simple, substantial, cheaply manufactured folding bed, in which counterweights, springs, and the like may be entirely eliminated, and in which the bed-frame proper may be raised and lowered by 10 means of a rack and pinion. Another object of the invention is to provide a removable foot-frame and foldable legs for the same to permit the bed structure as a whole to be folded into as compact a unit as possible when not in use. Further objects will 15 hereinafter appear.

The invention consists of the parts and the construction and combination of parts as hereinafter more fully described and 20 claimed, having reference to the accompanying drawings, in which—

Figure 1 is a side elevation of the bed.

Fig. 2 is an end view of same, partly broken away.

Fig. 3 is a cross section on line 3—3 of Fig. 1.

Fig. 4 is a detail view of the foot-frame, showing the construction of the folding legs.

Referring to the drawings in detail, A indicates the head-frame of the bed, 2 the mattress frame, and 3 the foot-frame. The several frames shown are preferably constructed of light tubing and are secured together by standard fittings, such as here 35 shown, and for the purpose of permitting the bed to be folded and to assume an upright position when desired a pair of extension side frames, such as shown at 4, have been provided. The mattress frame 2 is 40 pivotally mounted, as at 5, between the side frames 4, and while any suitable form of pivotal connection may be employed a U-shaped lug 6 adapted to receive a pintle is employed.

For the purpose of permitting the mattress frame to be easily raised or lowered with comparatively little effort even by a child, a pair of segmental rack members 7 have been employed. These racks are 45 secured one on each side of the mattress frame and they are so positioned as to intermesh

with a pair of pinions 8 secured upon a shaft 9 journaled transversely of the main head-frame A in bearings 10 formed on one of the tube fittings 11. The outer ends of the 60 shaft are square to receive a hand crank 12, and as this may be removed and applied when desired, it can readily be seen that the mattress frame may be easily raised or lowered by any one with comparatively little 65 effort. Any danger of the bed accidentally closing itself is in this instance entirely obviated as counterweights, springs, or like devices are not employed.

The bars 14, connecting the upper and 70 lower rails 15 and 16, respectively, of the head-frame, are curved at their lower ends, as shown at 17. The curve conforms with the sweep of the head end of the mattress frame and the racks 7 and serves as a guide 75 and support for the mattress, pillows and bedding when the bed is being raised, thereby preventing these from being displaced and also obviating the necessity of employing mattress clamps, straps, or the like at this 80 end of the bed. The foot end of the frame may, however, be provided with ordinary bedding and mattress clamps of any type desired.

For the purpose of permitting the bed 85 as a whole to consume as small a space as possible, when folded and not in use, it is desirable that the legs shown at 18 should be foldable. This is accomplished by pivotally connecting the same, as at 19, to the 90 lower edge of the foot-frame 3. A tube 20, slidably mounted on the upper end of each leg, is adapted to be lifted up, as shown in Fig. 1, to cover the pivotal connection and also to lock the legs against movement when 95 the bed is lowered. This tube, when moved into the position shown in Fig. 4, permits the legs 18 to automatically fold as the bed is raised, and while any suitable means may be provided for securing the sleeve 20 in 100 the locking position shown in Fig. 1, I prefer a friction sleeve which will automatically retain its place when raised.

The U-shaped lugs 6 employed permit the mattress frame as a whole to be quickly removed from the main frame A if it is desired to take the bed apart for shipping or storage and screws, such as shown at 21, are provided which also permit the foot-frame to be removed. The several units forming 110 the bed may, therefore, be separately packed or stored and as the manner of assembling

same is very simple it is obvious that it may be accomplished by any one.

The materials and finish of the bed as a whole may otherwise be such as the experience and judgment of the manufacturer may dictate.

I wish it understood that various changes in form, proportions and minor details of construction may be resorted to within the 10 scope of the appended claims and that I do not wish to limit myself to the specific design and construction here shown.

Having thus described my invention, what I claim and desire to secure by Letters Patent is—

1. In a folding bed of the character described, a head member consisting of main and supplemental vertical posts, top and bottom rails, and a plurality of vertically 20 disposed bars connecting said rails, the lower ends of the vertical bars having a concave curvature, and a mattress frame pivoted and turnable about the center of curvature of the said vertical bars, and said bars forming 25 a receptacle and guide for the head end of the bedding during the movement of the mattress frame.

2. In a folding bed, a vertical head frame having a forwardly curved guide at its lower

end between the sides thereof, and a bed 30 frame pivotally related to the head frame, the pivotal point of the bed frame being at the center of curvature of the forwardly curved guide whereby the bedding during the movement of the bed-frame engages said 35 guide so as to be controlled thereby.

3. In a folding bed, a vertical head frame having a forwardly curved lower portion, a bed frame pivotally related to the head frame, the pivotal point of the bed frame 40 being at the center of curvature of the lower portion of the head frame whereby said curved portion affords a guide for the bedding during movement of the bed-frame, racks of the same curvature as the lower 45 portion of the head frame borne by the bed-frame and having their centers of curvature at the pivotal points of the bed-frame, and means meshing with the racks to actuate the latter, said racks overlying the bed-frame at 50 the head end of the latter.

In testimony whereof I have hereunto set my hand in the presence of two subscribing witnesses.

CHRESTEN TORBEN MADSEN.
